Primary Examiner — Susan Bennett Hattan*Assistant Examiner* — Brett Miller(74) *Attorney, Agent, or Firm* — David G. Henry, Sr.(57) **CLAIM**

The ornamental design for a carbide chip, as shown and described.

DESCRIPTION

FIG. 1 is a front-side elevational view of a carbide chip in accordance with the present invention;

FIG. 2 is a front perspective view of the carbide chip in FIG. 1;

FIG. 3 is a back perspective view thereof;

FIG. 4 is a left side perspective view thereof;

FIG. 5 is a right side perspective view thereof;

FIG. 6 is a top perspective view thereof; and,

FIG. 7 is a bottom perspective view thereof.

The present invention is used on down-hole drilling tools.
